UNITED STATES PATENT OFFICE.

KENNETH HOWIE, OF NORRISTOWN, AND WILLIAM O. TAYLOR, OF LIMERICK, PENNSYLVANIA, ASSIGNORS TO WILDMAN MFG. CO., OF NORRISTOWN, PENNSYLVANIA, A CORPORATION OF PENNSYLVANIA.

DETECTOR AND STOP-MOTION MEANS FOR KNITTING MACHINES.

Original application filed February 21, 1920, Serial No. 360,440. Divided and this application filed August 8, 1921. Serial No. 490,647.

To whom it may concern:

Be it known that we, KENNETH HOWIE and WILLIAM O. TAYLOR, citizens of the United States, and residents of Norristown, 5 and Limerick, respectively, in the county of Montgomery and State of Pennsylvania, have invented certain new and useful Improvements in Detectors and Stop-Motion Means for Knitting Machines, of which the 10 following is a specification.

This specification is a division of that filed by us February 21, 1920, No. 360,440, patented August 1, 1922, Patent No. 1,427,625. It concerns among other features 15 yarn feeding means arranged as a detector for abnormal conditions existing at the point where the knitting is done, said feeding means, when operated as a consequence of the existence of said conditions, reducing 20 or stopping the draft of the yarn, and thereby causing stop motion means to operate to arrest the motion of the machine.

Other features of the invention will be 25 clear from the following description, taken in connection with the appended claims.

In the accompanying drawings:—

Figure 1 is a vertical sectional view taken radially of the machine, some of the parts being shown in elevation. 30 Fig. 2 is a front view looking from the center of the machine radially outwards, showing the yarn guide and some of the web holders or sinkers.

Fig. 2^a is a detail view looking from the 35 bottom of Fig. 2.

Fig. 3 is an enlarged view of the end of the yarn guide and a portion of a combined web holder and sinker.

Fig. 4 is a plan view of one of the sections 40 of the knitting machine.

In these drawings 1 is the needle cylinder which in the present illustration is the rotating part and 2 is the cylinder cam ring. The spring beard needles are shown at 4, 45 there being a single row of these. 4 is the sinker ring which is mounted on the needle cylinder and carries radially slideable sinkers 5, which also perform the function of web holder, being constructed for this two-fold 50 purpose with a yarn engaging and sinking

nose 6 and a web engaging and holding throat 7.

Individual needle beard pressers are shown at 8, held in place by a spring band 9 engaging their notches 10 so that the pressers can have rocking movement to advance to and retract from pressing position. 55

The thread guide consists of a sheet metal member 40 bent back upon itself with a space between its two sides for the passage 60 of the yarn.

This thread guide is carried by an arm or member 41, pivoted at 42, to a block 43 secured to the cam ring. The arm has a broadened upper end curved over at 44 and 65 having guide eyes 45 for the yarns. The pivoted arm is held in position against a stop pin 46 by a spring pin 47 having a conical end engaging a corresponding recess in the arm. Pressure exerted upon the arm 70 sufficient to overcome the holding force of the spring pin will throw the arm with its yarn guide backward and lift the yarn guide 41 from its yarn feeding position, shown in Fig. 2. It will be noticed that the end of 75 the yarn guide when in normal position is in the same horizontal plane in which the sinkers are arranged, but as shown in the plan view, Fig. 4, when the sinkers arrive at the position where the yarn guide is located, they are retracted as indicated by the 80 sinker wave s, s', in said Fig. 4, so as to pass outside of the said guide, after which the sinkers are advanced as at s² to sink the yarn between the needles. The edge of the yarn 85 guide is inclined downwardly at 41^a and should a sinker, by reason of breakage of its butt, not be retracted to proper position, and therefore strike the yarn guide, the latter will be swung up into the position substantially as indicated in dotted lines in Fig. 2, and the yarn will be lifted from feeding 90 position and its normal draft will be reduced and the stop motion therefor will be operated to stop the machine. 95

As an example of a suitable stop motion which may be used for this purpose, we would mention that disclosed in Letters Patent of the United States No. 1,316,929, Sept. 23, 1919. 100

We have illustrated herein at A, Fig. 1, the ring and one of the yarn fingers of the said stop motion. When the draft on the yarn is materially reduced or ceases, this 5 finger will drop and operate the stop motion connections to stop the machine.

The yarn guide is adapted to direct a main and a plating yarn to the needles as indicated in Fig. 2. One of these yarns is 10 guided under the front wall 41^a of the yarn guide arm and the other yarn is directed below the division piece 41^b which lies between the sides of the yarn guide and is riveted or pinned thereto.

15 Features not claimed herein have been made the subject of claims in application No. 490,648, filed August 8, 1921, and Patent No. 1,445,767 dated February 20, 1923.

We claim:—

20 1. In combination, needles, a series of instruments, one for each needle cooperating therewith, means for operating them, a stop motion device rendered operative by a reduction or cessation of the draft of the yarn, 25 and a member movably mounted and displaced from normal position by contact with a disabled instrument to withdraw the yarn from normal feeding position and thereby reducing or stopping the draft 30 thereon, substantially as described.

2. In combination, needles, instruments co-operating therewith, means for operating the same, a yarn guide extending to the feeding point, said guide being pivotally 35 mounted to be moved from its normal position when acted on by a disabled instrument, and stop motion means held in normal position by the draft of the yarn and arranged to operate to stop the machine when the 40 draft of the yarn is reduced or ceases consequent upon the yarn guide moving from normal position, substantially as described.

3. In combination, needles, means for operating the same, a yarn guide pivotally 45 mounted and extending from its pivot downwardly and forwardly in the direction in which the needles travel and presenting an inclined under edge, instruments co-operating with the needles and having a 50 back and forth movement and stop motion means rendered active by reduction or cessation of the draft of the yarn consequent upon the yarn guide moving from its normal position by contact with a disabled instrument at or adjacent the yarn feeding point, causing pressure to be exerted on the yarn guide through said inclined edge to move the guide from its normal feeding 55 position, substantially as described.

60 4. In combination in a circular knitting machine, knitting instruments, a yarn guide, stop motion means controlled by the draft of the yarn running therethrough to the 65 yarn guide, said yarn guide being movably mounted to be displaced from its normal

feeding position as a consequence of contact with a disabled instrument, whereby the normal draft of the yarn will cease and the stop motion will operate, substantially as described.

5. In combination in a circular knitting machine, knitting instruments, a yarn guide, stop motion means controlled by the draft of the yarn running therethrough to the 70 yarn guide, said yarn guide being movably mounted to be displaced from its normal feeding position as a consequence of contact with a disabled knitting instrument, whereby the normal draft of the yarn will cease and the stop motion will operate, said 75 stop motion means being located at the axial center of the machine, substantially as described.

6. In combination in a circular knitting machine, knitting instruments, a yarn guide, stop motion means controlled by the draft of the yarn running therethrough to the 80 yarn guide, said yarn guide being movably mounted to be displaced from its normal feeding position as a consequence of contact with a disabled knitting instrument, whereby the normal draft of the yarn will cease and the stop motion will operate, said 85 stop motion means being located at the axial center of the machine, substantially as described.

7. In combination in a knitting machine, needles with operating means therefor, a set of instruments cooperating with the needles in knitting, means for operating said instruments, a yarn guide movably mounted and contacting with a disabled instrument to be moved by said contact from normal position, and stop motion means controlled 90 by the movement of the yarn guide, substantially as described.

8. In combination in a knitting machine, needles with operating means therefor, a set of instruments cooperating with the needles in knitting, means for operating said instruments, a yarn guide movably mounted and contacting with a disabled instrument to be moved by said contact from normal position, and stop motion means controlled by the 95 movement of the yarn guide, said instruments consisting of radially movable members which are normally retracted to pass the yarn guide from their advanced positions between the needles, substantially as described.

9. In combination in a knitting machine, needles with operating means therefor, a set of instruments cooperating with the needles in knitting, means for operating said instruments, a yarn guide movably 100

mounted and contacting with a disabled instrument to be moved by said contact from normal position, and stop motion means controlled by the movement of the yarn guide, 5 said instruments consisting of radially movable sinkers which are normally retracted to pass the yarn guide, and said guide being pivotally mounted and having its yarn delivery portion in substantially the same horizontal plane with the noses of the sinkers, 10 substantially as described.

10. In combination in a knitting machine, needles, yarn measuring sinkers operating between the needles to bend the yarn between them, a yarn guide for directing the 15 yarn to normal feeding position in front of

the sinkers, a stop motion device held in normal position by the draft of the yarn and arranged to operate for stopping the machine when the draft of the yarn is reduced or ceases, said yarn guide being shiftable from normal feeding position by contact with a disabled sinker, and when shifted withdrawing the yarn from normal feeding position in front of the sinkers, 20 and from the needles and thereby reducing draft thereon, substantially as described. 25

In testimony whereof, we affix our signatures.

KENNETH HOWIE.
WILLIAM O. TAYLOR.
